WALTER CONNOR, OF WINDSOR, ONTARIO, CANADA.

LIFTING JACK.

1,413,655.

Specification of Letters Patent. Patented Apr. 25, 1922.

Application filed November 17, 1920. Serial No. 424,676.

To all whom it may concern:

Be it known that I, WALTER CONNOR, of city of Windsor, in the county of Essex, Province of Ontario, Canada, have invented 5 certain new and useful Improvements in Lifting Jacks, of which the following is a specification.

This invention relates to lifting jacks of the lever type, and my object is to provide 10 a simple, strong and reliable jack which will be double acting either in lifting or lowering.

I attain my object by means of the constructions hereinafter described and illustrated in the accompanying drawings in which—

Fig. 1 is a side elevation, partly in section, of my improved jack;

Fig. 2 a front elevation of the same; 20 Fig. 3 a side elevation of part of the jack, partly in section, illustrating the mode of operation in lowering the sliding bar;

Fig. 4 a cross section on the line *a—b* in Fig. 2; and

Fig. 5 a horizontal section through the lifting lever showing particularly the trunnions of the lifting lever and the pawls.

In the drawings like numerals of reference indicate corresponding parts in the different figures.

1 is a standard provided with a suitable base 2. On this standard the lifting bar 3 is vertically slidable in any ordinary manner. Members 4 integral with the standard 35 extend up at each side from the upper end of the standard. These members at their upper ends are provided with projections 5 adapted to extend into grooves 6 formed in the sides of the lifting bar. By 40 this arrangement of the members 4, sufficient of the lifting bar between the guiding points is exposed to the operation of the lifting lever.

The lifting lever 7 is forked to embrace 45 the lifting bar as shown, and is provided with trunnions 8, which are adapted to enter open bearings 9 formed in the member 4. The lifting lever is thus readily removable when the lifting bar is not in position.

50 On the lifting lever are pivoted the depending pawls or dogs 10, which are adapted to engage ratchet teeth 11 formed on opposite faces of the lifting bar. The ratchet teeth on one face of the bar are preferably 55 arranged in staggered relationship to the teeth on the opposite face of the bar, so

that the lift of the lever on one stroke is equal to half the tooth spacing, thus providing ample leverage without an undue length of lever. With this arrangement the 60 pawls 10 may be pivoted exactly opposite one another instead of in staggered relationship as would otherwise be necessary. The pawls, it will be seen, operate alternately, so that the lifting movement is obtained 65 both on the up stroke and downstroke of the lever. As the pawls hang from the lifting lever, the strains of lifting are applied advantageously thereto and the jack is both easy in operation and durable. 70

To permit of the lifting bar being lowered by the same up and down movement of the lifting jack, I provide the following mechanism. The stem 12 is slidably supported on the standard to move longitudinally thereof 75 adjacent the pawls 10 at each side thereof. This stem is normally upwardly pressed by a coil spring 13. The stem carries a head 14 adapted to be engaged by the inclined planes 15 formed on the sides of the pawls. 80 When extended, this head is so positioned that the inclined plane on a pawl engages the head when the pawl has arrived approximately at its limit of downward movement, the pawl being thus forced away from the 85 adjacent face of the lifting bar to thus disengage from the ratchet tooth with which it has been engaged.

From this construction it follows that the lifting bar will be lowered the space of 90 one tooth at each double stroke of the lifting lever 7.

The upward movement of the head 14 must, of course, be limited and means provided for pushing the head down out of the 95 way when the jack is to be used in lifting. For this purpose I provide a cam lever, which is integrally formed, comprising a cam 17 at its inner end, a journal 18, and the lever handle 16. A bearing is formed 100 in the adjacent member 4 in which the journal fits. The parts of the cam lever are so shaped and proportioned that it may be introduced into the bearing by pushing the handle 16 through from the inside until 105 the journal comes into position in the bearing. I find it necessary to provide a notch 19 at one side of the outer end of the bearing to permit of this being done. It is evident that by suitably actuating the handle 110 16 that the head 14 may be depressed or allowed to move upwardly under the action

of the coil spring 13 as may be required. The pawls 10 are connected by a coil spring 20. As this spring acts in opposition to the coil spring 13 when the inclined planes 5 engage the head 14, the spring 20 must be of sufficient strength to overcome the tension of the spring 13 when the load on the lower pawl is relieved by the rising pawl on the opposite side engaging the lift 10 ing bar.

It will be noted that as the pivots of the pawls 10 are formed as trunnions 27 integral with the pawls and as the pivots of the lifting lever 7 are formed as trunnions 15 8, the centers on which the pawls rock may be set very close to the center on which the lever rocks without weakening either the lever or the pawls, thus ensuring ample lifting leverage on the pawls and enabling the 20 pivots to be made of large size to ensure ample bearing surface. This arrangement of the pivots of the pawls necessitates the provision for introducing the trunnions 27 into their bearings, such for example, as the 25 dividing of the socket of the lifting lever 7 on a vertical plane the parts being secured together by rivets 28.

To provide points of engagement with the lifting bar other than the head of the same, 30 I provide the auxiliary lifting bar 21, which is provided at its upper end with a hook member 22 adapted to fit over the head of the lifting bar 3. The latter is provided with a nose 23 which passes through an 35 opening formed in the upper end of the auxiliary lifting bar. The lower end of the auxiliary lifting bar is provided with lugs 24 which carry a roller which fits between the sides of guide ribs 25 formed on the stand- 40 ard 1. The auxiliary lifting bar is thus easily placed in position and when in position is suitably guided. One or more shoul- 45 ders 26 are formed on this auxiliary lifting bar for engagement with the parts to be lifted.

What I claim as my invention is:—

1. In a jack, the combination of a stand- 50 ard; a lifting bar slidable therein and having downwardly facing ratchet teeth formed at opposite faces thereof; members extending up from the upper end of the standard at each side and having open bearings formed therein at their inner sides below their upper ends, said upper ends being adapted to guide 55 the sliding bar; a forked lever embracing the sliding bar and provided with trunnions adapted to be received in said open bearings; and depending dogs pivoted on the lever at opposite faces of the bar and adapted to engage the ratchet teeth thereon.

2. In a jack, the combination of a stand- 60 ard; a lifting bar slidable therein and having downwardly facing ratchet teeth formed at opposite faces thereof, and also having vertical grooves formed in its opposite sides;

members extending up from the upper end of the standard at each side and having open bearings formed therein and projections above the bearings extending into the grooves in the sides of the lifting bar; a forked lever embracing the sliding bar and provided with trunnions adapted to be received in said open bearings; and depending dogs pivoted on the lever at opposite faces of the bar and adapted to engage the ratchet 75 teeth thereon.

3. In a jack, the combination of a stand- 80 ard; a lifting bar slidable therein and having downwardly facing ratchet teeth formed at opposite faces thereof; a forked lever ful- crumed on the standard and embracing the sliding bar; depending dogs pivoted on the lever at opposite faces of the bar and adapted to engage the ratchet teeth thereon; and pawl releasing means movable to and from a 85 pawl engaging position comprising a vertically movable, spring-extended stem and a head, each pawl being adapted, when the releasing means are suitably positioned, to engage said head on reaching its lowermost 90 position and to be swung outwardly thereby.

4. In a jack, the combination of a stand- 95 ard; a lifting bar slidable therein and having downwardly facing ratchet teeth formed at opposite faces thereof; a forked lever ful- crumed on the standard and embracing the sliding bar; depending dogs pivoted on the lever at opposite faces of the bar and adapt- 100 ed to engage the ratchet teeth thereon; a pawl releasing means movable to and from a pawl engaging position, each pawl being adapted, when the releasing means are suitably positioned, to engage said releasing 105 means on reaching its lowermost position; a spring tending to hold said pawl releasing means in their operative position; and a cam lever journaled in the standard adapted to releasably hold the pawl releasing means in their inoperative position.

5. In a jack, the combination of a stand- 110 ard; a lifting bar slidable therein and having downwardly facing ratchet teeth formed at opposite faces thereof; a forked lever ful- crumed on the standard and embracing the sliding bar; depending dogs pivoted on the 115 lever at opposite faces of the bar and adapt- ed to engage the ratchet teeth thereon; a stem slidable longitudinally of the standard; a spring tending to raise the stem; a head on the stem extending into proximity to the 120 pawls; an inclined plane on each pawl adapted to engage the head, when the stem is extended and the pawl is in its lowermost position, to disengage the pawl from the slid- 125 ing bar; and means for releasably holding the head depressed to an inoperative position.

6. In a jack, the combination of a stand- 130 ard; a lifting bar slidable therein and having downwardly facing ratchet teeth formed at opposite faces thereof; members extend-

ing up from the upper end of the standard at each side; a forked lever embracing the sliding bar and journalled in said members; depending dogs pivoted on the lever at opposite faces of the bar and adapted to engage the ratchet teeth thereon; a stem slideable longitudinally of the standard adjacent one of the upwardly extending members; a spring tending to raise the stem; a head on the stem extending into proximity to the pawls; an inclined plane on each pawl adapted to engage the head, when the stem is extended and the pawl in its lowermost position, to disengage the pawl from the sliding bar; and means for releasably holding the head depressed comprising an integral cam lever formed with a head engaging cam, a journal and a lever handle, the adjacent upwardly extending member having a bearing formed therein through which the lever

handle may be passed to position the journal in the bearing.

7. In a jack, the combination of a standard having open bearings formed therein; a lifting bar slideable therein and having downwardly facing ratchet teeth formed at opposite sides thereof; a forked lever embracing the sliding bar and provided with integral trunnions adapted to be received in said open bearings; and depending dogs at opposite faces of the bar adapted to engage the ratchet teeth thereon and provided with integral trunnions having bearings in the said forked lever. 25

Signed at Windsor Ontario this fifth day 30 of November 1920.

WALTER CONNOR.
